UNITED STATES PATENT OFFICE.

GUSTAVE C. MARX, OF ELIZABETH, NEW JERSEY, ASSIGNOR TO DIEHL MANUFACTURING COMPANY, A CORPORATION OF NEW JERSEY.

ELECTRICAL CONTROLLER.

SPECIFICATION forming part of Letters Patent No. 739,433, dated September 22, 1903.

Application filed July 2, 1903. Serial No. 164,007. (No model.)

To all whom it may concern:

Be it known that I, GUSTAVE C. MARX, a citizen of the United States, residing at Elizabeth, in the county of Union and State of New Jersey, have invented certain new and useful Improvements in Electrical Controllers, of which the following is a specification, reference being had therein to the accompanying drawings.

10 This invention relates to an improvement in that class of controllers which are employed more particularly in connection with electric sewing-machine motors and are mounted upon the tables or work-benches by which the driven machines are carried. Heretofore the accumulation of foreign matter, and particularly of lint from the sewing-machines to the tables of which these controllers have been associated, has in some cases been the cause 15 of fire due to the ignition of such accumulated matter upon and around the operative parts of the device by the arc produced in breaking the electric circuit when stopping the machine.

20 25 The present invention has for its object to so incase the operative parts of the controller as to effectively exclude the dust and other foreign matter which has heretofore caused such trouble, and to thus obviate the danger 30 of fire from such cause and also to prevent the deterioration of the device from its operation when clogged with such foreign matter.

The invention consists, essentially, in a casing for the operative parts of the controller 35 and comprising a flat base member formed with a cover-seat, to which is closely fitted and removably secured a cover for closing the casing dust-proof, combined with a contact-lever with its operative portion insulated from and 40 wholly inclosed within said casing, but having a spindle passing through the wall of the latter by a dust-proof joint and provided upon its outer end with an operating arm or lever. In its preferred form the cover-seat 45 is disposed somewhat below the level of the usual series of contact-points and adjacent segmental contact-plate, and the contact-lever is mounted upon the cover member of the casing, so that the removal of the latter exposes 50 the contact-surfaces for brightening up after

their effectiveness has been impaired in some degree by extensive use of the device.

The invention will be understood by reference to the annexed drawings, in which—

Figures 1 and 2 are detached views of the 55 component members of the casing with their attached operative parts, Fig. 1 being a plan of the base member and Fig. 2 a perspective view of the cover member, taken from the under or inner side. Fig. 3 is a transverse section of the controller with the parts carried thereby in operative relation.

The base member consists of a flat plate *a*, having a recess *b* in its lower side, which is closed by means of the bottom plate *c*, secured 65 in position by the bolt *d*. Upon its upper side the plate *a* is provided with a marginal cover-seat *e*, surrounding a segmental projection *f*, upon which, with suitable interposed insulation, is secured a segmentally-arranged 70 series of live contact-points *g* by means of the insulated screws *h*, passing through the plate *a* and connected upon the opposite face of the latter, each with the ends of two adjacent members of a series of resistance-coils *i*, 75 of which the opposite ends are similarly connected with other said contact-points of the series. Adjacent said live contact-points *g* is an insulated "dead" contact-point *j*, having no permanent electrical connection with 80 other live parts of the device.

The live contact-point *g* farthest from the dead-point *j* is connected, by means of a wire *k*, with a binding-post *l*, constituting one pole of the controller, the other pole of which 85 is a second binding-post *l'*, connected by a wire *k'* with the insulated segmental contact-plate *m*, secured upon two insulating-washers *n* by screws *n'*.

The cover member *o* of the casing is fitted 90 closely to the cover-seat *e* of the base-plate *a* and secured thereto by screws *p*, its side walls inclosing the contact-points *g* and *j* and the contact-plate *m* and the two-part contact-lever mounted upon the inner end of a spindle 95 *q*, which is journaled in and extends through the upper or outer wall of the cover member *o* and has upon its outer end the operating arm or lever *r*.

The contact-lever has one of its parts *s* 100

rigidly secured to the inner end of the spindle, its outer part *t* being secured thereto by means of insulated screws *u*, passing through an interposed strip *v* of insulating material, 5 such as vulcanized fiber, by means of which it is insulated from the other part *s* and the casing *a o*.

The outer or operative portion of the part *t* is provided with a socket *t'* to receive the 10 loosely-fitted carbon contact-block *w*, pressed inwardly by one end of a flat spring *x*, having its other end attached to the part *t* of the contact-lever by means of a screw *y*.

The cover member *o* is formed with an aperture *o'* for access to the operative parts of 15 the device for purposes of adjustment and inspection, such aperture being normally closed by means of a cover-plate *z*.

Having thus described the invention, what 20 I claim herein is—

1. In an electrical controller, the combination with a dust-proof casing comprising a flat base member having a cover-seat and a cover member fitted closely to and secured 25 removably upon said seat, of a connected series of resistance-coils, a series of insulated contact-points connected with said coils and a contact-plate insulated from said contact-points, all mounted upon said base member 30 of the casing, a spindle journaled in and extending through the wall of said casing, a contact-lever fixed upon the inner end of said spindle and having its operative portion insulated therefrom and adapted to establish 35 electrical connection between said contact-plate and contact-points, and an operating arm or lever secured upon the outer end of said spindle exterior to said casing.

2. In an electrical controller, the combination 40 with a dust-proof casing comprising a flat base member having a marginal cover-seat and a cover member fitted closely to and secured removably upon said seat, of a connected series of resistance-coils, a series of 45 insulated contact-points connected with said

coils and a contact-plate insulated from said contact-points, all mounted upon said base member of the casing but projecting above its cover-seat, a spindle journaled in and extending through the wall of said cover member, a contact-lever fixed upon the inner end of said spindle and having its operative portion insulated therefrom and adapted to establish 50 electrical connection between said contact-plate and contact-points, and an operating arm or lever secured upon the outer end of said spindle exterior to said cover member.

3. In an electrical controller, the combination with a dust-proof casing comprising a 60 base member having a cover-seat and a cover member fitted closely to and secured removably upon said seat and provided with an aperture for access to the contents of said casing, of a series of insulated contact-points 65 connected with said coils and a contact-plate insulated from contact-points, all mounted upon said base member of the casing, a spindle journaled in and extending through that portion of the wall of the cover member having 70 said aperture, a two-part contact-lever mounted upon the inner end of said spindle with its operative portion insulated therefrom and provided with a socket, a contact-block mounted loosely in said socket, a flat 75 spring carried by said lever beneath said aperture in the cover member and adapted to press said contact-block upon said contact-plate and points, a cover-plate secured removably upon the outer face of said cover 80 member to cover its said aperture, and an operating arm or lever fixed upon the outer end of said spindle exterior to said casing.

In testimony whereof I have signed my name to this specification in the presence of 85 two subscribing witnesses.

GUSTAVE C. MARX.
